UNITED STATES PATENT OFFICE.

SAMUEL S. MATTHES, OF MANSFIELD, OHIO, ASSIGNOR TO THE OHIO BRASS COMPANY,
OF MANSFIELD, OHIO, A CORPORATION OF NEW JERSEY.

CURRENT-COLLECTING DEVICE.

Application filed November 18, 1921. Serial No. 516,034.

To all whom it may concern:

Be it known that I, SAMUEL S. MATTHES, a citizen of the United States of America, residing at Mansfield, in the county of Rich-
5 land and State of Ohio, have invented cer-
tain new and useful Improvements in Cur-
rent-Collecting Devices, of which the follow-
ing is a specification.

My invention relates to current collecting
10 devices and more particularly to that class
of collectors used with trolley busses which
travel to either side of the center line of the
trolley wires or directly in line therewith.

The object of my invention is a device
15 which is cheap, simple and efficient for col-
lecting current from two conductors of dif-
ferent polarities at the same time permitting
the bus to swing to either side of the
trolley wires.

20 Another object is to produce a device
which will operate steadily and will not
"nose" when one collector encounters an ob-
struction such as a supporting ear or splicer
as is the case if the collector head sets at
25 right angles relatively to the two wires.
When the head is positioned diagonally to
the trolley wires, the wires tend to maintain
a parallel position and any attempt for one
collector to nose ahead of its normal position
30 when it strikes an obstruction in the wire
and thus set up a vibrating action of the
whole head is obviated.

Another object of my invention is to pro-
duce a device which will automatically take
35 care of a variation in the spread or spacing
of the trolley wires.

Another object is to provide means to pre-
vent the collector head from catching on the
overhead, should the collector leave the wire.

40 My invention resides in the construction,
combination and arrangement of parts more
fully hereinafter set forth.

In the drawings accompanying this speci-
fication:—

45 Fig. 1 is a top plan view of my invention.
Fig. 2 is a side elevation view of my inven-
tion.

In the preferred form herein shown, I em-
ploy a pole 1, secured at its lower end to a
50 bus, in the usual manner of devices of this
nature, by a base exerting an upward spring
pressure on the pole. To the upper end of

the pole I secure a support member 2 having
a socket 3 to receive the pole and a socket
4 to receive a yoke member 5 in pivotal rela-
tion thereto and secured in position by the
55 nuts 6 on the lower end of the yoke mem-
ber 5.

Pivottally mounted on the yoke member
by means of the pin 7 is a head 8 formed
60 of insulating material. Secured to each end
of the head 8 is a collector support member
9 held in position by the bolts or pins 10.
The collector support is provided with arms
65 11 between which is rotatably mounted a
current collector wheel 12 on the pin 13.
The length of the head 8 and the angular
position of the collector 12 on the head 8 are
70 such that the head 8 is compelled to take a
diagonal position with respect to the wires,
75 and the tendency of the wires to maintain a
fixed distance therebetween tends to main-
tain this diagonal relation.

In order to prevent the head from readily
catching in the overhead construction, should
75 one or both collectors leave the wires, I pro-
vide the members 14 preferably of insulat-
ing material and secured to the members 9
at their upper edge, and in order to main-
tain them in position at their lower end and
80 permit the members 1 and 8 to pivot relatively
to each other, I place a sheave 15 as shown
and secured to the pole 1 by the member 16
and pass around the sheave 15 a flexible
85 member 17 secured to the members 14. The
members 14 as described will prevent the col-
lectors 12 from becoming caught above the
trolley wire.

To each member 9 is a socket 18 adapted to
receive a conductor by means of which the
90 current is led from the collector to the trol-
ley-bus.

The construction of my device is such
that in the operation, the trolley bus is per-
mitted to travel directly below the trolley
wires in line therewith or to swing to either
side of the wires and travel parallel ther-
ewith. The distance between the collectors
95 12 along the axis of the head 8 being greater
than the perpendicular distance between the
wires, the head will take a diagonal position
relatively to the wires and any tendency
for the head to change this normal diagonal
100 relation will be counteracted by the result-

ant forces acting on the wires to maintain them in their normal position. This diagonal relation of the head to the wires will prevent the head from "see-sawing" about its pivot point at 4, which it is found to do if the distance between members 12 is equal to the distance between the wires, in which case not "see-sawing" of the head is the result but severe swinging of the wires is set up and the head thrown from the wires.

The head also operates to accommodate itself to any reasonable inequalities in the spacing of the wires or variation in their height.

Various modifications may be made from the disclosure herein shown and described but still falling within the scope of my invention.

20 I claim:—

1. A current collector for gathering current from two adjacent conductors comprising a support, a member secured to the end of the support, a member pivotally mounted on the first said member, an insulated member pivotally mounted on the second said member, a support member secured to each end of the insulated member, a current collecting member secured to each last named support member to engage the conductors, and means so associated with a plurality of the supports as to prevent the device catching on the conductors.

35 2. A current collector for gathering current from two adjacent conductors comprising a support, a member secured to the support, a member mounted on the first said member, an insulated member mounted on the last said member, a support member secured to each end of the insulated member, a current collector mounted on each last named support to engage the conductors and means associated with the first said support to prevent the device catching on the conductors.

40 3. A current collector for gathering current from two adjacent conductors comprising a support, a member secured to the support, a member mounted on the first said member, an insulated member mounted on the last said member, a support member secured to each end of the insulated member, a current collector mounted on each last named support to engage the conductor and insulated means secured to the support and insulated member to prevent the device from catching on the conductors.

45 4. A current collector for gathering current from adjacent conductors comprising a support member, a plurality of current collecting members each to engage a conductor, spaced from each other and from the support, the distance between the collecting members being greater than the per-

pendicular distance between the conductors, means to permit the collecting members to pivot relatively to the support in a substantially horizontal plane and means to permit the collecting members to pivot relatively to the support in a substantially vertical plane.

5. A current collector for gathering current from adjacent conductors comprising a support member and a head mounted on the support member, the head provided with a plurality of current collecting members each to engage a conductor and spaced and insulated from each other and from the support, the distance between the collecting members being greater than the normal perpendicular distance between the conductors.

6. A current collector for gathering current from adjacent conductors comprising a support member, a plurality of current collecting members each to engage a conductor, spaced from each other and from the support, the distance between the collecting members being greater than the perpendicular distance between the conductors.

7. A current collector for gathering current from adjacent conductors comprising a support member, a plurality of current collecting members each to engage a conductor, spaced from each other and from the support and mounted to pivot in a plane substantially parallel to the plane of the conductors, the distance between the collecting members being greater than the perpendicular distance between the conductors.

8. A current collector for gathering current from adjacent conductors comprising a support member, a plurality of current collecting members each to engage a conductor, spaced from each other and the support and mounted to pivot about an axis approximately at right angles to the plane of the conductors, the distance between the collecting members being greater than the perpendicular distance between the conductors.

9. A current collector for gathering current from adjacent conductors comprising a support, a plurality of current collecting members each to engage a conductor and means to secure the collecting members to the support and maintain the distance between the collecting members greater than the normal perpendicular distance between the conductors, the said means having an axis obliquely disposed to the conductors.

10. A current collector for gathering current from adjacent conductors comprising a support, a plurality of current collecting members each to engage a conductor and mounted on the support and means to maintain the separation of the collecting members greater than the normal separation of the

conductors and mounted to pivot about an axis substantially parallelly and obliquely disposed to the conductors.

11. The combination with a trolley pole, of a cross-head pivotally supported thereon, a plurality of current conductors mounted on said cross-head, and flexible guard means extending from spaced points on the cross-head to a point adjacent the trolley pole and about a sheave mounted on said pole.

12. The combination with a trolley pole, a plurality of current collecting means each to engage a conductor, supporting means to maintain the collecting means in a predetermined pivotal relation to the support and guard means fixedly secured to the supporting means at a plurality of spaced points and movably secured to the trolley pole to permit the supporting means to pivot.

13. The combination with a pair of conductors of a pair of current collecting members each to engage a conductor, and obliquely disposed means to maintain one of the collecting members in advance of the other at all times.

14. The combination with a current collector head provided with a support and a plurality of current collecting members to engage conductors, of means secured to the head at a plurality of spaced points and movably secured to the support to protect the head against entanglement with the conductors.

15. A current collector to gather current from adjacent conductors comprising in combination a support member and a head mounted on the support and having its axis obliquely disposed to the conductors, the head provided with a plurality of collecting members each to engage a conductor and spaced and insulated from each other and mounted in pivotal relation to the support and means to maintain the collecting members out of perpendicular alignment with the conductors.

16. The combination with a current collector head provided with a support and a plurality of current collecting members to engage conductors of insulated members secured to the head and the support to protect the head against entanglement with the conductors.

17. The combination with a support of

current collecting members spaced and insulated from each other, means secured to the support to maintain the collecting members in spaced insulated and pivotal relation to the support and guard means secured to the said means and to the support and capable of having its length automatically changed as the relation of said means changes relative to the support.

18. The combination with a trolley pole, of a cross-head pivotally supported thereon, two current collectors mounted adjacent to opposite ends of the cross-head, and a guard arm extending from each end of the cross-head to a point adjacent to the trolley pole.

19. The combination with a trolley pole, of a cross-head pivotally supported thereon, two current collectors disposed at opposite sides of the trolley pole, and a guard arm extending from each end of the cross-head to a point adjacent to the trolley pole, the guard arm being movable relatively to the pole.

20. The combination with a trolley pole, of a cross-head pivotally supported thereon, current collectors disposed at opposite sides of the trolley pole, and a guard arm extending from the cross-head on each side of the trolley pole to the trolley pole, the guard arms being adjustable relative to the trolley pole such that when one arm lengthens the other shortens as and for the purpose described.

21. The combination with a trolley pole, of a cross-head pivotally supported thereon, current collectors disposed at opposite sides of the trolley pole, and a guard arm extending from the cross-head on each side of the trolley pole to the trolley pole, the guard arms being automatically adjustable relative to the trolley pole as the head pivots relative to the trolley pole.

22. The combination with a pair of conductors, of a pair of current collecting members each to engage a conductor, obliquely disposed means to maintain one of the collecting members in advance of the other at all times, means to support said means and guard means extending from said first means to the support to prevent entanglement of the device with overhead conductors.

In testimony whereof I affix my signature.
SAMUEL S. MATTHES.
